(57) CLAIM

The ornamental design for a dog, as shown and described.

DESCRIPTION

FIG. 1 is a side perspective view of a dog;

FIG. 2 is a top perspective view thereof;

FIG. 3 is a right elevational view thereof;

FIG. 4 is a left elevational view thereof;

FIG. 5 is a front perspective view thereof;

FIG. 6 is a back perspective view thereof;

FIG. 7 is a top plan view thereof;

FIG. 8 is a bottom plan view thereof;

FIG. 9 is a partial left perspective view thereof, shown broken away for ease of illustration;

FIG. 10 is a partial right perspective view thereof, shown broken away for ease of illustration; and

FIG. 11 is a top perspective view thereof.

The broken lines shown in the drawings illustrate portions of the dog that form no part of the claimed design.
